UNITED STATES PATENT OFFICE.

LOUIS H. FEDER, OF CLEVELAND, OHIO, ASSIGNOR OF ONE-HALF TO RICHARD S. BONDY, OF CLEVELAND, OHIO.

CURTAIN-SUPPORTING MEANS FOR AUTOMOBILE DOORS.

Application filed May 6, 1922. Serial No. 558,996.

To all whom it may concern:

Be it known that I, LOUIS H. FEDER, a citizen of the United States, and a resident of Cleveland, county of Cuyahoga, and State 5 of Ohio, have invented a new and useful Improvement in Curtain-Supporting Means for Automobile Doors, of which the following is a specification, the principle of the invention being herein explained and the 10 best mode in which I have contemplated applying that principle, so as to distinguish it from other inventions.

The present invention relates to the construction of automobile doors and means in 15 conjunction therewith, for supporting and holding the side curtains which are so made as to open with the doors, and to this end the door is made with a pocket in which the folded curtain is adapted to be stored, and 20 this pocket is also provided with means for supporting the curtain when the same is to be raised. The present invention relates particularly to improvements and modifications of the general construction shown in 25 my co-pending application curtain support for automobile doors, filed June 27, 1921, Serial No. 480,507. To the accomplishment of the foregoing and related ends, said invention, then, consists of the means hereinafter 30 fully described and particularly pointed out in the claims.

The annexed drawing and the following description set forth in detail certain mechanism embodying the invention, such dis- 35 closed means constituting, however, but one of various mechanical forms in which the principle of the invention may be used.

In said annexed drawing:—

Fig. 1 is an elevational view of the inside 40 of a door showing the curtain arrangement in its supported position and the folded arrangement of the curtain and support in dotted lines; Fig. 2 is a sectional view on the line 2—2 of Fig. 1; Fig. 3 is an elevational view similar to Fig. 1 but showing a modified form of construction; Fig. 4 is a 45 section on the line 4—4 of Fig. 3; Fig. 5 is an elevational view similar to Figs. 1 and 3 but showing a slightly different constructional form; and Fig. 6 is a sectional view 50 on the line 6—6 of Fig. 5.

In the present construction there is shown a typical automobile door 1, which, as usually constructed, comprises a substantially 55 rectangular framework 2 provided exterior-

ly with a thin sheet 3 of metal or equivalent material, the inner side of the frame being covered with leather or other fabric material 4 having a large opening therein which is preferably covered by a flap 5 so as to 60 form a sort of a pocket 6 within the door.

In the present construction there is mounted within the pocket a horizontal rod 7 which is suitably attached to the door frames and this rod 7 is preferably mounted 65 close to the top frame of the door, as best shown in Figs. 1, 3 and 5. On this rod is carried the curtain support which in the form shown in Fig. 1, comprises a metal strap 8 having an apertured ear 9 at one end 70 at right angles to the plane of the strap, this apertured ear 9 being mounted on the rod 7 so as to be slidable therealong as well as rotatable about the same. The body portion of the strap is curved at an angle so 75 that when the strap is revolved about the rod, the outer end 10 of the same will be at a level with the top of the door, and this outer end is bent so as to fit flat against the horizontal top 12 of the door, and this end 80 is provided with a sleeve 13 arranged to stand vertically when the strap is in position on the door top, as best shown in Fig. 1.

This sleeve is provided with a longitudinal slot 14, and in the sleeve is mounted the 85 lower end of the curtain support rod 15 which is provided with a pin 16 engaging in the slot 14 so as to allow this rod to have limited movement through the sleeve in order that the lower end of the rod may be 90 moved downwardly into a suitable socket 17 formed in the upper frame of the door, thus locking the rod and supporting strap in position to support a curtain. As shown, the 95 rod is provided with an off-set 18 so as to bring the vertical line of the rod out to the edge of the door or slightly beyond the same, in order to obtain the necessary over-lap between the curtain 20 which is carried by the rod and the next adjacent curtain (not 100 shown) on the automobile. As shown in all of the elevational views, the curtain support rod is provided with a joint 21 at about its central point, a slidable sleeve or the like 22 being mounted on the rod to hold the two 105 parts in upright position when the curtain is to be raised. In the present construction, a jointed rod or the like is necessary because, as best shown in Fig. 1, when it is desired 110 to remove the curtain from the car, the sup-

port rod will be raised out of the door socket and the curtain will then be folded with the jointed rod after the curtain is unsnapped from the door, and the entire device will be 5 folded down into the door pocket by, first, sliding the strap along the horizontal rod in the pocket to the position shown in dotted lines in Fig. 1, and the curtain and folded rod may then be folded down into the 10 pocket by rotating the strap about the rod so that the whole device is folded compactly into the pocket, as best shown in Fig. 1.

In order to allow the curtain to be thus folded, it is preferably provided with four 15 lights 23 of transparent material spaced apart by strips 24 and 25 of fabric, the horizontal strip 24 through the center of the curtain being in line with the folding joint 21 in the support rod and the vertical strip 20 25 between the transparent lights being approximately in the center of the curtain so that the device will fold into a neat rectangular package carried by the support rod at all times.

25 A slightly modified form of construction is shown in Figs. 3 and 4 in which the curtain support and rod is formed of a single piece, the lower portion of the support having a hollow sleeve 30 mounted on the horizontal rod 7 and slideable and rotatable thereon. This sleeve is integrally attached to a horizontal portion 31 of the support which is then bent at right angles and is provided with a short offset 32 before extending again 30 at right angles to the horizontal portion 31 to form the support rod for the curtain proper, and the small right angle portion 32 is provided with a pin 34, and this vertical portion 32 is adapted to be slid into a socket 35 at the side of the top door frame and the pin is adapted to be dropped into suitable slots 36 in this socket member to secure the support and rod in its vertical upright position. In operation this form is 45 essentially like the first, the sleeve 30 sliding along the supporting rod in the pocket and being rotatable thereabout so that the curtain support rod may be folded down in the pocket, as shown in dotted lines in Fig. 3.

50 In the third form which is illustrated in Figs. 5 and 6, the construction is essentially similar to that in the second form inasmuch as there is a sleeve 40 mounted on the horizontal pocket rod 7 which carries a horizontal support 41 having two successive offsets or step portions 42 and 43 terminating in the upright curtain support rod 44, and one of these offset portions is provided with a loop 45. The top frame member of the 55 door is slotted with the slot 46 running from the inner face of the door along the same and into the door slightly, and within this slot is fixed a cross pin 47 over which the loop 45 portion of the support rod is adapted to be engaged in order to hold the folded

curtain support and rod in its upright position. In this case the sleeve 40 which is mounted on the horizontal pocket rod is short and is comparatively loose on the rod in order to obtain the necessary rocking 70 movement to allow the loop to be engaged over the pin in the door slot. In action this form is similar to the others, the sleeve being slideable along the pocket rod in order to be brought in position adjacent the edge 75 of the door and rotatable about this rod so that the support rod may be raised into its curtain holding position along the door edge, or lowered into its folded position, as shown in dotted lines in Fig. 5.

80 The present forms, as previously stated, are modifications of construction shown in my co-pending application, and they make use of the same principle of construction whereby the curtain support is movable along the upper edge of the door, that is, from front to back, and is also pivotally mounted about this horizontal support so that the curtain may be folded down within the door pocket below the upper framework 85 of the door, and thus the upper edge of the door is left closed as in the usual door construction except for the usual socket opening or the like, and the curtain and support may be stowed away together without 90 danger of the curtain rods becoming bent and the curtain becoming detached or lost from the rod, and it is always in a position to be readily raised. Furthermore, by means of the usual flap on the pocket, the curtain and supporting means are out of sight when housed, and the door is in all respects the usual door which is always supplied with a 95 socket for the curtain support, where the automobile is supplied with door opening 100 curtains.

105 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

115 1. In a device of the character described, the combination of a vehicle door having a top frame member and a pocket below said member, of a rod mounted in said pocket below said frame member, a support member 120 slideably mounted on said rod and rotatable thereabout and a curtain support rod carried by said support member and movable therewith from a position above said top frame member to a position below the 125 same within said pocket.

2. In a device of the character described, the combination of a vehicle door having a top frame member and a pocket below said member, of a rod mounted in said pocket be- 130

low said frame member, a support member 5
slidably mounted on said rod and rotatable
thereabout and a curtain support rod carried
by said support member and movable there-
5 with from a position above said top frame
member to a position below the same within
said pocket, and means on said top frame
member adapted to engage with said support
member and rod to lock the same in their
10 position above said frame.

3. In a device of the character described,
the combination of a vehicle door having a
top frame member and a pocket below said
member, of a rod mounted in said pocket
15 below said frame member and extending
longitudinally of said door, a support mem-
ber slidably mounted on said rod and rotat-
able thereabout, and a jointed curtain sup-
port rod carried by said support member,
20 said curtain rod being foldable and movable
with said support member longitudinally
along said rod rotatably about the same from
its curtain supporting position above said
top frame member to a position below the
25 same entirely within such pocket.

4. In a device of the character described,
the combination of a vehicle door having
a fixed top frame member, and a pocket be-
30 low the same opening on the inside of said
door, a foldable curtain, a rod mounted in
said pocket and extending longitudinally of
said door, a support member slidably mount-
ed on said rod and rotatable about the same,
35 a jointed curtain rod attached to said sup-
port member and adapted to be attached
to said curtain, said support rod and curtain
being foldable and then being movable about
said rod as an axis and along the same to
40 move said curtain, support rod and support
member from the curtain raised position to
its folded position below said top frame
member entirely within such pocket.

5. In a device of the character described,
the combination of a vehicle door having
45 a solid top frame member and a pocket be-
low the same open to the inside of said
door, a rod mounted within such pocket be-
low said top frame member and extending
longitudinally of the door, a support mem-
50 ber having an apertured ear rotatably

mounted on said rod and slidably therealong,
said rod being curved and provided with an
apertured end set at an angle to the support
member and adapted in its upward position
55 to rest on said top frame member, and a
curtain support rod carried by said support
member and movable therewith and adapted
in one position to extend vertically upward
at the edge of said door and in the other
60 position to be mounted within such door
pocket.

6. In a device of the character described,
the combination of a vehicle door having a
solid top frame member and a pocket be-
65 low the same open to the inside of said door,
a rod mounted within such pocket below said
top frame member and extending longitudi-
nally of the door, a support member having
an apertured ear rotatably mounted on said
70 rod and slidably therealong, said rod being
curved and provided with an apertured end
set at an angle to the support member and
adapted in its upward position to rest on
said top frame member, a sleeve on
75 said support member and a curtain support
rod slidably mounted in said sleeve, and a
socket in said top frame member adapted
to receive the end of said curtain support
rod to secure said curtain support rod and
80 said support member in their upward posi-
tion.

7. In a device of the character described,
the combination of a vehicle door having a
solid top frame member and a pocket be-
85 low the same open to the inside of the door,
a horizontal longitudinally extending rod
mounted in such pocket below said top
frame member, a support member and cur-
tain support rod comprising a sleeve rotat-
90 ably mounted on said rod and movable there-
along, and having an offset portion adapted
to allow said curtain support rod to extend
vertically upward from above said top frame
member, and means on said door for engage-
95 ment with said support member and curtain
rod and adapted to receive them in raised
curtain holding position.

Signed by me this 2 day of May, 1922.

LOUIS H. FEDER.
